Primary Examiner — Calvin E Vansant*Assistant Examiner* — Sydney M Evans(57) **CLAIM**

The ornamental design for the bendable moss pole assembly, as shown and described.

DESCRIPTION

FIG. 1 is a front elevational view of the bendable moss pole assembly, showing my new design;

FIG. 2 is a rear elevational view thereof;

FIG. 3 is a left side view thereof;

FIG. 4 is a right side view thereof;

FIG. 5 is a front view, in which the bendable moss pole assembly is shown in a first bent configuration;

FIG. 6 is a front view, in which the bendable moss pole assembly is shown in a second bent configuration;

FIG. 7 is an enlarged partial view of the portion marked “7” in FIG. 1; and,

FIG. 8 is an enlarged partial view of the portion marked “8” in FIG. 5.

There is no claim to color or shade.

There is no claim to contrasting color or contrasting shades. The short-long dash broken lines indicate bounds of the enlargement views and form no part of the claimed design.
